UNITED STATES PATENT OFFICE.

MIDDLETON D. BROWN, OF WATERLOO, IOWA.

SWITCH.

1,194,134.

Specification of Letters Patent.

Patented Aug. 8, 1916.

Application filed December 21, 1915. Serial No. 68,049.

To all whom it may concern:

Be it known that I, MIDDLETON D. BROWN, a citizen of the United States, residing at Waterloo, in the county of Blackhawk and 5 State of Iowa, have invented certain new and useful Improvements in Switches; and I do hereby declare the following to be a full, clear, and exact description of the invention, such as will enable others skilled in 10 the art to which it appertains to make and use the same.

This invention relates to new and useful improvements in switches and more particularly to that type of switch adapted for use 15 in connection with pocket flash lights, and the principal object of the invention is to provide a switch which insures positive action of the contacts thereby insuring a continuous flow of current through the light 20 and preventing the light from flickering or accidentally going out.

Another object of the invention is to provide a means for locking the switch in its inoperative position to avoid the possibility 25 of the device being accidentally lighted thereby using the power without any necessity therefor.

With these and other objects in view, the invention consists in the novel combination 30 and arrangement of parts which will be fully set forth in the following specification and accompanying drawings, in which:—

Figure 1 is a plan view from the exterior of a flash light showing this improved 35 switch applied thereto. Fig. 2 is a longitudinal sectional view on line 2—2 of Fig. 1. Fig. 3 is a transverse sectional view on line 3—3 of Fig. 1, and Fig. 4 is a view in detail of the contact and illustrating the wiring 40 diagram of the device.

Referring to the drawings, the numeral 1 designates a flash light of the ordinary character provided with the usual lens 2. The switch used in connection with the device is 45 designated generally by the numeral 3 and comprises the transversely U-shaped metallic body 4 having the attaching wings 5 formed integral with the ends of the arms thereof. These attaching wings are provided with suitable openings for the reception 50 of the attaching screws 6 by means of which they are secured to the exterior of the flash light casing as clearly shown in Fig. 1. The opposite ends of the U-shaped body 4 55 are turned downwardly as at 7 to provide

stops to prevent the slide from passing beyond a predetermined point.

The slide above referred to is designated generally 8 and comprises the shaft 9 having formed thereon the enlarged thumb piece 60 10 which projects upwardly through a slot 11 in the body 4 and provides a means by which the shaft may be moved. A suitable enlarged head 11' is formed at one end of the slide and is adapted for engagement with 65 the clip designated by the numeral 12 comprising the U-shaped body 13 having the ends of the thumb bent inwardly as at 14 and again bent outwardly as at 15 so as to engage the head 11 and hold the same in 70 the position shown in Fig. 4. When in this position it will be seen that the current through the light will be discontinued and due to the fact that the inwardly bent portions 14 engage the rear walls of the head, it 75 will be seen that accidental movement of the shaft 9 is prevented. The end of the shaft 9 opposite the head 11 is provided with a tapered portion 16 which is adapted to engage the contact 17 comprising a U-shaped body 18 having the ends of its arms formed with the inwardly offset parallel contact arms 19, the outer ends of which are bent outwardly as at 20 to form guides in which the portion 16 slides. 85

It will be apparent from the foregoing that in use the current passes from the battery through the usual spring and into a suitable conductor to the body 4. It will thus be seen that the frictional contact between the body and the shaft 9 will cause said shaft when the point 16 is moved into engagement with the contact arms 19 to complete the circuit through the switch 17 and to the lamp bulb in the forward end of the 95 casing by means of a suitable conductor and thence back to the opposite contact of the battery through the center contact to the lamp. It will thus be seen that a steady 100 flow of current through the light is provided which will avoid the flickering and necessity of holding the thumb on the contact during the time the light is used.

While in the foregoing there has been shown and described the preferred embodiment of this invention, it is to be understood that such changes may be made in the combination and arrangement of parts as will fall within the spirit and scope of the appended claim. 110

What is claimed is:—

- A switch for flash lights comprising a transversely U-shaped body, wings on the free edges of the arms of the body adapted 5 to provide a means by which the switch is attached to a flash light, a clip within the body at one end, a stationary contact at the opposite end of the body, a sliding contact comprising a shaft, a pointed extension at 10 one end of the shaft adapted to engage the stationary contact, the body being provided with a longitudinal slot, a thumb piece on the shaft extending through the slot provid-

ing a means by which the sliding contact is moved and a head at the end of the shaft 15 opposite the contact end adapted to enter the clips to hold the sliding contact away from the stationary contact when the device is not in use.

In testimony whereof I affix my signature 20 in presence of two witnesses.

MIDDLETON D. BROWN.
